(57) **CLAIM**

The ornamental design for a vehicle grille, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front right perspective view of a vehicle grille. FIG. 2 is a front left perspective view of the vehicle grille shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front right view of the vehicle grille shown in FIGS. 1-10, with the vehicle grille mounted on a vehicle, and the rest of the vehicle shown in de-emphasized and half-tone portions to illustrate environmental structure, which portions form no part of the claimed design.

More particularly, in FIG. 11, the vehicle grille is shown within the broken line, and the elements shown outside the broken line form no part of the claimed design, but are instead included to show environmental aspects thereof.

In FIG. 11, the smaller broken line located inside the vehicle grille, in a circular badge shape, represents an unclaimed boundary.
